UNITED STATES PATENT OFFICE

2,005,475

ELECTRICAL CONNECTER

Edward F. Schmidt, Spokane, Wash.

Application June 1, 1932, Serial No. 614,803

1 Claim. (Cl. 173—343)

My present invention relates to an improved electrical connector adapted for use at the end of the cord or wires of electrical appliances, and designed to make the electrical connection with the well known type of electrical plug that is threaded into a wall socket, or outlet. Thus in carrying out my invention the connector is permanently attached at the end of the cord or wires employed on an electric iron, a lamp, toaster, or other household appliance of this type, and in making the connection for illuminating the lamp (for instance) my improved connector is "plugged in" to the usual plug that has previously been secured in the wall socket.

By the utilization of the connector of my invention, the usual friction-held mechanical and electrical connection may be made with facility between the prongs or blades of the connector and the complementary socket-walls of the plug, or a positive, mechanical, lock, in addition to the friction-held connection, may be accomplished between the connector and the socket-plug. Means are provided whereby strains imparted through a pull on the cord or wires, (as when grasping the wire and jerking the connector from the plug, by hand) are prevented from reaching the terminals of the connector, thereby preserving the terminal connections and avoiding loosening of the wires.

The improvements involved in the new connector also involve a novel, resilient and flexible handle for the connector to be grasped by hand when making or unmaking the connection to the wall-plug. The invention consists in these, and other novel combinations and arrangements of parts as will hereinafter be more fully set forth and claimed.

In the accompanying drawing I have illustrated one complete example of the physical embodiment of my invention wherein the parts are combined and arranged according to the best mode I have thus far devised for the practical application of the principles of my invention.

Figure 1 is a side view of my connector applied to and positively locked on the usual threaded plug for a wall socket or outlet.

Figure 2 is a longitudinal sectional detail view of the device of Figure 1.

Figure 3 is a face view of the connector.

Figure 4 is a perspective view of the grip or clamp device mounted within the connector for gripping the wires or cord.

The connector of my invention is designed for use with the well known type of plug 1, having the screw-threads 2 for screwing into a comple-

mentary socket, or pocket in an outlet box, and this plug has the usual spaced sockets 3 that accommodate the prongs or blades found on most connectors now in use. In converting the screw plug 1 to my own use I equip the plug with a pair of laterally extending, diametrically arranged, pins 4, 4, having heads 5, 5. These pins may be screws, as indicated in Figure 2, that are threaded into the plug, or the pins may be embedded in the plug when the latter is cast.

The connector plug 6 of my invention is cylindrical in shape, of insulating material, and provided with an axial bore or hole 7, and the round enlargement or head 8 is fashioned with an annular flange F on its face to provide a depression therein. The annular, rear face 9 of the head forms an annular shoulder for use in retaining a loosely mounted cup-shaped sleeve 10 on the connector. This sleeve has a hole 11 fitting neatly about the exterior of the connector, and the diameter of the sleeve is such as to fit the sleeve neatly over the exterior faces of the head of the connector and the outer end of the threaded plug 1.

The free edge of the cylindrical sleeve is provided with a pair of diametrically arranged bayonet slots 12, 12 that are adapted to co-act with the pins 4, 4, of the screw plug in locking the sleeve and connector to the screw plug. A spring 13 is coiled about the exterior of the connector, within the sleeve and between the shoulder 9 of the connector and the end of the sleeve, and the tendency of this spring is to push the sleeve away from the front face of the connector, or away from the screw plug when the connector, is attached to the screw plug. Thus, the sleeve is provided with a knurled ring 14 by means of which the sleeve may be pushed toward the screw plug, against the tension of the spring 13, to cause the slots 12 to slip over the pins 4, and then by a twist or turn of the sleeve, the bayonet slots are engaged with the pins in such manner as to lock the sleeve and the connector to the screw plug. For releasing the lock joint, the sleeve is turned in reverse direction, to free the bayonet slots from the pins, and then the spring is free to project the sleeve to the right in Figures 1 and 2. A stop ring 15 is fixed at the rear end of the connector, on its periphery, to limit the movement of the sleeve under action of the spring.

A pair of spaced blades or prongs 16 and 17 of usual type project from the face of the connector, for insertion into the two complementary sockets or holes 3, 3, of the screw plug, and it will be understood that these prongs or blades adapt

the connector of my invention for use with the usual screw plugs, as well as for use with the converted screw plug 1 illustrated herein.

The blades or prongs are integral with arcuate 5 terminal arms or plates 18, that are secured by screws 19, against the flat face of the head 8, within the depression of the face of the head of the connector, and the ends of the wires 21 are provided with terminal loops 23, through which 10 the screws pass. The face of the connector is countersunk at 22, and grooved as at 23 to accommodate the wires and the terminals or loops, and the latter are firmly secured by the screws. The wires are passed through the hole or bore 15 7 of the connector, and they also pass through a flexible and resilient handle or knob 24 that is secured at the rear end of the connector.

This handle or knob is fashioned, preferably, 20 of rubber and is soft and elastic for convenience in handling, and may be grasped between the fingers and thumb when the connector is to be attached to or detached from the screw plug. The handle is fashioned with an exterior, annular flange 25, and the rear end of the connector is provided with an inwardly projecting flange 26 that forms a grooved seat 27 to receive the flange of the handle, and retain the handle by the flange 25.

In the seat 27 a washer or circular disk 28 is 25 mounted transversely of the bore of the connector and of the handle 24, and this disk, which is countersunk on one side at 29 is provided with a central opening 30 having tapering walls. As best seen in Figure 2, the maximum diameter of 30 this tapered opening is approximately the same as the bore of the connector, while the minimum diameter is considerably less than the bore 1. Thus, the flexible tapering walls 30 will permit the wire or cord to be passed, from right to left 40 in Figure 2 through the bore of the connector, in order that the wires may be connected to the terminal screws, and as the wire is thus passed, the tapering walls are slightly spread or forced open. Under these conditions, the tapering walls 45 form a jaw that grips the cord, the elasticity or resiliency of the material of the jaw holding the cord out of contact with the hard surface of the bore of the connector, and avoiding abrading of the insulation on the cord. This gripping jaw 50 also serves to take the strains of a pull on the cord, away from the terminal connections of the wire. As is the custom with many people, in detaching the connector from the screw plug, the detachment is made by grasping the cord or wire 55 and giving the latter a jerk. This effectually detaches the connector, but it is also likely to

disconnect the terminals of the wires. When the connector is equipped with the grip of my invention, and a jerk is given to the wire or cord, this action causes the tapering walls or jaw to grip the cord with a cam action, and the grip of the disk on the cord causes the strain of the jerk to be imparted to the connector, through the disk, instead of being imparted or translated through the wire to the wire-terminals.

As herein described and illustrated it will be 10 apparent that I have provided an electrical connector that is comparatively inexpensive in cost of manufacture, which is simple in construction, and durable, and well adapted to withstand careless manipulation in use. The device is suitable 15 for employment in shops, factories, offices, homes, and other places, for making positive and secure connections with various electrical appliances, which may be locked in position, when desired, to avoid the annoyance caused by plugs being 20 pulled out of their sockets. The locking device, when used, is especially adapted where the screw plug and the connector are employed as an overhead suspension connection, and the cords or wires suspend the electrical appliance, as a lamp. 25 Under these conditions, the weight of the load is taken off the frictionally engaged prongs or blades, and is borne by the bayonet slot and pin connection, and the grip 30 also takes the weight of suspension off the terminals of the wires, thus 30 avoiding strain at the terminals.

Having thus fully described my invention, what I claim as new and desire to secure by Letters Patent is:—

The combination with an electrical connector 35 having an enlarged head forming an annular shoulder, said head having a recessed face and means therein for making electrical contact with a plug, and a spaced stop ring on the exterior of the reduced body of the connector, of a cylindrical cup shaped locking sleeve mounted on the head projecting over the body of the connector having an annular inturned flange and longitudinally slidable on the body of the connector, said flange adapted to co-act with said stop ring, 40 and a spring enclosed by the sleeve coiled about the body of the connector and interposed between and abutting against said shoulder and said flange, whereby the free end of the sleeve projects a distance over the plug equal to the 45 distance between the inturned flange and the stop ring in order to bring the connector flush with the edge of the sleeve when said connector is disengaged from said plug for ready access to 50 said electrical contact means.

EDWARD F. SCHMIDT.
